UNITED STATES PATENT OFFICE.

FRED M. OPITZ, OF RACINE, WISCONSIN, ASSIGNOR TO PERFEK RADIATOR COMPANY, OF RACINE, WISCONSIN, A CORPORATION OF WISCONSIN.

METHOD OF FORMING SHEET METAL.

1,316,636.

Specification of Letters Patent. Patented Sept. 23, 1919.

Application filed October 11, 1918. Serial No. 257,764.

To all whom it may concern:

Be it known that I, FRED M. OPITZ, a subject of the Emperor of Germany, and a declarant of intentions of becoming a citizen of the United States, having taken out my first papers, residing at Racine, in the county of Racine and State of Wisconsin, have invented a certain new and useful Improvement in Methods of Forming Sheet Metal, of which the following is a full, clear, concise, and exact description, reference being had to the accompanying drawings, forming a part of this specification.

My invention relates to a method of forming sheet metal.

While the invention is particularly useful in connection with the formation of radiator tubes, I do not intend to limit the invention to such use or purpose only.

Radiator tubes made up of single pieces of sheet metal have been previously known, and I do not lay claim to such broadly, although the particular radiator construction resulting from this herein claimed process is novel and is claimed as such in my pending case, Serial No. 200,252, filed March 5, 1917, of which the present application is an improvement.

For the sake of efficient operation, it is desirable to make the tubes with as large a superficial radiation area as possible and to bring all parts of the water or the cooling medium near the radiating surfaces to cool the contents of the tubes. It is also desirable that the walls of the tubes through

which transfer of heat is to be accomplished should be as thin as mechanical strength will permit. To be able to make the tube out of sheet metal is desirable, because of the

cheapness of such sheet metal and because of the strength of the tubes when thus formed. There is also a strong demand for a pleasing appearance of the radiator. To meet these requirements I form the tubes out of sheet metal with lateral corrugations

of such form as to provide, when these tubes are assembled into a core, a number of round cylindrical passages for the air between the corrugations of adjacent tubes. The particular formation which I employ gives the appearance of a solid block with a large number of closely grouped cylindrical air passages through the core with a series of vertical fins or flanges between rows of cir-

cular holes where the fold or seam along the front face of each tube is made. The holes of one vertical row are offset by one-half the pitch distance with respect to the holes of adjacent rows so that a maximum number of holes is possible.

This arrangement requires the offsetting of the corrugations of the tube and such offsetting has heretofore been a practical difficulty because of the uneven drawing of the metal, as heretofore practised.

To form the circular holes it is necessary that the tubes have lateral corrugations forming complete halves of the sides of the holes. The tubes are made of a thickness substantially equal to the diameter of the holes and semi-circular depressions lie on each side of the central flange or seam. The front and rear faces of the tubes are made to lie as nearly as possible in planes parallel to the front and rear faces of the core in the preferred form of my invention, although this is not essential. The corrugations are, in the preferred form of my invention, at right angles to the face of the core, but this also may be varied.

I am aware that heretofore tubes have been made with corrugations along the sides and that said tubes have been made of a single sheet of metal, but no one heretofore has produced a tube having complete semi-circular depressions to form complete circular holes so that the air within the hole is in contact with the cooling medium on all sides.

Furthermore the production of a semi-circular depression with a substantially square integral end flange is novel and has not heretofore been produced.

I have found it possible to produce such a radiator tube through the discovery of a novel principle of working the sheet metal, and it is with the application of this novel principle of working sheet metal that the present application is concerned.

I have found that where it is desired to produce a corrugated metal tube or part of a tube in which the side walls are to be corrugated and the end walls are to be plain, that the metal along the margins which form the end walls may be shrunk sufficiently to supply the extra material or metal required to form the corrugations.

This is opposed to the teachings of the

prior art in which the marginal portions are maintained at their original thickness and the parts to be corrugated are stretched in order to supply the surplus required for the 5 corrugations.

The general principle involved is that where a plain sheet of metal is to be distorted out of a plane shrinking of one part of the metal or sheet may be accomplished 10 under certain conditions with better effect and more easily than stretching or expanding the other part. The decision between shrinking and stretching should be made upon the basis of the amount of metal that 15 must be moved by one as against the other, and by any special difficulties which would be involved. Another subsidiary principle that is involved relates to the matter of forming the metal about a sharp shoulder or 20 projection. Where the shoulder or projection is of such a character or shape that the metal would be stretched along a sharp line or point, I find that it is possible to shrink or fold the metal about the form or projection so as to leave the desired shape without damage to the metal in any way.

In order to explain to those skilled in the art the manner in which these principles are to be applied in actual working of sheet 30 metal, and to explain a specific embodiment of the invention, I shall now describe in connection with the accompanying drawings the manufacture of radiator tubes for forming the core of a radiator.

35. In the accompanying drawings—

Figure 1 is an isometric view of a part of the core of a radiator employing tubes constructed in accordance with my invention;

Fig. 2 is a fragmentary front elevation of 40 a radiator core of the form shown in Fig. 1;

Fig. 3 is a diagrammatic illustration in isometric projection of the sheet of metal formed according to the first step of my invention;

45. Fig. 4 is a similar diagrammatic view in isometric projection showing the step of corrugating the bottom and edge wall of each of the gutters or grooves shown in Fig. 3;

50. Fig. 5 is a fragmentary isometric view illustrating diagrammatically the manner in which the metal is shrunk along the flanges, that is the marginal portion, and the end walls to form the semi-circular corrugation;

55. Fig. 6 is a front elevation of a part of the finished corrugation showing the manner in which the metal has been folded along the end walls of the tube or part of the tube;

Fig. 7 is a fragmentary sectional view 60 taken from the inside with respect to Fig. 6 showing the manner in which the metal is folded inwardly along the end walls of the tube;

Fig. 8 is a sectional view taken on the 65 line 8-8 of Fig. 6 showing the folding and

thickening of the metal along the margin and end walls of the tube;

Figs. 9 to 21 inclusive illustrate various steps in the manufacture of commercial 70 radiator tubes.

Fig. 9 is a plan view of a sheet passing through the first stage of folding to form the margins and end walls of the tube;

Fig. 10 is an end view of the same;

Figs. 11 and 12 are a plan view and an 75 end view respectively of the second step which consists in forming the corrugation in the sides of the tube and shrinking the ends and margin;

Figs. 13 and 14 are plan view and end 80 view respectively of the sheet after it has been moved forward one pitch distance in the dies.

Figs. 15 and 16 are plan view and end 85 view respectively of the sheet after it has advanced completely through the dies showing the creasing along the central margin for folding;

Fig. 17 is a plan view of the corrugated and creased sheet after it has been trimmed 90 in preparation for folding;

Fig. 18 is an end view of the same taken from the left of Fig. 17;

Fig. 19 illustrates the step of folding the 95 central margin and starting the fold of the edge margin, which step is accomplished by a power press;

Fig. 20 is an end view of the tube after the fold has been completed and the seam 100 has been closed at the one edge of the tube; 105 and

Fig. 21 is a side view of the completed tube taken from the left of Fig. 20.

The radiator which I preferably form is of the vertical tube type having suitable 110 headers at the upper and lower ends of the tubes, these tubes being grouped together in contact to form a solid core, a section of which is illustrated in Fig. 1. The core 1 comprises the series of tubes 2 which have water passageways 3 passing vertically through the same. The side walls of the tubes 2 are provided with the semi-circular 115 depressions or corrugations 4 between which remain the flat side walls 5 which are placed in contact with adjacent similar walls of the tubes on each side of the particular tube. These semi-circular depressions, when thus brought into register, form the cylindrical 120 holes or air passageways 6 through which the air for cooling the liquid within the core 1 passes, with the flanges or seams 7 and 8, which are formed respectively by folding the sheet and by joining the free 125 margins, as will be described later.

To form the tubes I provide a strip of sheet metal of suitable width and thickness and preferably of soft copper or brass which is run through a suitable set of dies, such as disclosed in my copending applica- 130

tion Serial No. 257,765, filed October 11, 1918. The tube might be made up of two sheets of metal one for each side but preferably I form both sides simultaneously and 5 form the tube by folding along a center margin, as will be described later.

The sheet 10 is fed into suitable dies which form the sheet into the double gutter shown at the right of Fig. 9 and shown in 0 Fig. 3. The two gutters 11 and 12 are formed with the side margins 13 and 14, respectively, and the central margin 15 which forms the folding margin to form the complete tube. While I have shown in 5 Fig. 3 a complete gutter formed in this manner, it will be understood that the step of corrugating the gutter as fast as it is formed is found in practice to be preferable, as these operations may be performed by a 10 single pass through a suitable stamping or punch press, as is described in my copending application. The gutter 11 has the bottom wall 16 which becomes the side wall of the tube when completed, and the end walls 17 and 18 which become the front and rear end faces of the tube when completed.

The gutter 12 is similarly formed with the bottom wall 19 and the end walls 20 and 21. A description of the operation of forming one gutter will suffice for both. The depth of the gutters 11 and 12 is substantially half of the thickness of the finished tube.

So far in forming the tube, the metal has 5 not been disturbed, either by stretching or shrinking, except as to bending along the corners. The die which forms the gutters 11 and 12 is inclined so that the gutter is formed gradually as it is fed forward to 10 the corrugating parts of the dies. The sheet, as shown in Figs. 9 and 10, is then advanced to the corrugated part of the dies where the semi-circular corrugations 22 are formed. As is explained in my copending 15 application, the dies first form the gutters then the gutters are advanced by a feeding mechanism and the succeeding stroke of the dies first corrugates a part of the gutter and thereafter flattens out the margins and ex- 20 tends the formation of the gutter. Reference is made to said application for a disclosure of a commercial form of corrugating die press. The corrugations 22 in the gutter 11 are offset with respect to the corruga- 25 tions in the gutter 12 by one-half the pitch distance so that the circular holes 6 formed between tubes are staggered by the same amount. The first step in the corrugating dies forms a complete corrugation at 22 in 30 the gutter 11 and half of a corrugation in the gutter 12, as shown in Figs. 11 and 12. Thereafter the sheet is advanced by a strip equal to the pitch distance between corruga- 35 tions, the second step being illustrated in Figs. 13 and 14.

As these corrugations 22 are formed, the metal along the margins 13, 14 and 15, and along the end walls 17, 18, 20 and 21 is thickened by shrinking, this being indicated by the shading 23 and the increased thickness indicated in Figs. 12, 14 and 16. The thickness at the points indicated by the reference numeral 23 in these figures is exaggerated so that the same may be shown upon the drawing. In actual practice the 70 sheet 10 from which the tubes are made is initially of a thickness of substantially five thousandths of an inch. The margins and end walls are thickened by the corrugating operation until they reach a thickness of 80 substantially nine thousandths of an inch. I shall explain this matter of shrinkage of the metal more in detail in connection with Figs. 4 to 8-inclusive.

After the sheet has been passed through 85 to the rear part of the dies, the metal along the central margin 15 is given a slight crease, as indicated at 24, by a suitable groove and projection upon the co-operating part of the dies. During the corrugating operation the 90 thickening of the metal along the margins and end walls results in forming on the surfaces of these parts a great number of small surface wrinkles which are indicated by the shading 23. The forming of the line 24 95 which is in the nature of a very slight crease is to insure that all of the surface wrinkles have been flattened out along the line where the folds is to be formed. Hence this line 24 which I term a crease need be formed only 100 to the extent of insuring that there are no transverse wrinkles running across the central part, which creases, if they did exist, would tend to form a ragged or uneven fold.

The flattening out of the surface wrinkles 105 caused by shrinkage of the sheet does not produce an absolutely flat surface, as the wrinkles are still visible, but for practical purposes these surface irregularities are im- 110 material.

After the sheet has been completely corrugated it is cut into suitable lengths, and the margins 13 and 14 which are to form the seam are then trimmed by running the sheet through a suitable shears which is 115 guided along the central groove 25 formed between the walls 18 and 20. It will be noted that the margin 13 is of less width than the margin 14. This is for the purpose of forming a folded seam. The corrugated sheet shown in Figs. 17 and 18 is then placed in a suitable die and is folded along the line 24 on the central margin 15, as indicated in Fig. 19, and the edge of the margin 13 is bent up as shown at 26 in Fig. 19. The tube in the condition shown in Fig. 19 is then laid in a suitable die and is struck with another die which closes the seam 8 by folding the metal of flange 13 over the edge of the flange 14 into a folded seam, as 125 130

shown in Fig. 20. A series of such tubes are then grouped together into a core, the front and rear faces preferably, but not necessarily, being dipped in solder to cause union 5 between the adjacent portions 5 and to close the folded seam 27 where the margins 13 and 14 have been joined.

I shall now endeavor, in connection with Figs. 3 to 18 inclusive, to make clear the 10 movement of the metal in forming the corrugated tubes. When the double gutter, as shown in Fig. 3, is formed, the metal is nowhere warped as the margins 13, 14 and 15 lie in substantially the same plane, and the 15 end walls 17, 18, 20 and 21 lie in substantially parallel planes except for the small amount of taper necessary in practice to give clearance to the dies. This taper has been somewhat exaggerated in the drawings. Considering the gutter 11 shown in Fig. 3, independently of the gutter 12, as it is obvious that the formation of one is similar to the other, in order to secure the corrugations 4 there must be greater lineal 20 length of material in the bottom wall 16 than in the flanges 13 and 15 for the very obvious reason that the circumference of the semicircle is considerably greater than the diameter of the semicircle. In order to produce this surplus of material either the 25 metal in the bottom wall 16 and in a part of the end walls 17 and 18, must be sufficiently stretched to produce this surplus or the surplus of metal must be secured in some 30 other manner. Independently of which way it is secured, I believe that I am the first to form an open trough or gutter and then corrugate the bottom of the gutter with the corrugations running through the end walls.

35 The particular manner in which I secure the surplus metal for forming the corrugations is by shrinking the metal along the margins 13 and 15 and, to a certain extent, the end walls 17 and 18. Consider the gutter 40 40 after it has been corrugated, and it will be seen that the part of it, as shown in exploded or dissected form in Fig. 4, will consist of thickened margins 13' and 15' and thickened end walls 17' and 18' and the corrugated side walls 16' of original thickness. It is at once apparent, on comparing Figs. 3 and 4, that the end walls 17 and 18 must take up a relatively large proportion of the metal. Not only must enough metal be taken out to form the rounded scallops, 49, but also the end walls must be sufficiently fore-shortened endwise to reduce them from the original length to the less length, which the metal occupies after being corrugated 55 as shown at 16' in Fig. 4.

The manner in which this surplus metal is taken up by the end walls 17' and 18' will be better understood from Figs. 5 to 8 inclusive. Considering a single element of the gutter 11, as shown in Fig. 5, and the changes

in the metal which it must undergo, it will be seen that the length as shown in full lines must be contracted to the length shown between dotted lines 28 and 29, and the edge 30 of the bottom wall 16 must be drawn in 70 to the dotted lines, must be displaced laterally in order to permit the corrugations to run through the end wall. As the cylindrical die member pushes the bottom wall upward and crushes the end walls 17 and 18, 75 the metal within those portions of the end walls is partly taken up by thickening of the metal between corrugations in the end walls and is also partly taken up by crumpling or folding as is indicated in Figs. 6, 7 and 8. 80 There is both an outward folding, as shown at reference numeral 33, and an inward folding as shown at reference numeral 34 in Figs. 6, 7 and 8. This disposition of the metal can be clearly seen in the tubes after 85 they are formed.

As I have above explained, there is a tendency for surface wrinkles to form along the margins and along the end walls. This may be permitted to a greater or less extent, depending upon the closeness of the fit of the die. 90

I do not intend to be limited to the precise details shown and described as my invention, as relating to the formation of corrugated tubes and the like, is broadly new.

I claim:

1. In the method of forming a corrugated metal tube, the combination of the following steps: first forming a gutter having bottom 100 walls and end walls and marginal portions, and then corrugating the bottom wall with corrugations which run through the end wall.

2. The method of forming a corrugated 105 metal tube having uncorrugated portions which comprises shrinking the uncorrugated portions to provide a surplus of metal required along the corrugated portions.

3. The method of forming a metal tube 110 having corrugations along part of its walls which comprises shrinking the uncorrugated portion of the walls and simultaneously increasing the thickness thereof while maintaining the portions of the walls to be corrugated at substantially the original thickness. 115

4. The method of forming a metal tube having corrugations along part of its walls which comprises shrinking the uncorrugated 120 portion of the walls and simultaneously increasing the thickness thereof while maintaining the portions of the walls to be corrugated at substantially the original thickness, and corrugating said latter portion.

5. The method of forming a sheet metal tube having corrugated side faces and uncorrugated end faces which comprises the following steps: corrugating the side faces while maintaining them at substantially 125

original thickness and simultaneously shrinking the end faces to increase their thickness.

6. The method of forming a sheet metal tube having corrugated side faces and uncorrugated end faces which comprises the following steps: corrugating the metal comprising the side faces while maintaining said metal at substantially original thickness, simultaneously shrinking the end faces to increase their thickness and thereafter forming a seam along the end faces.

7. The method of forming a corrugated metal tube having uncorrugated portions which comprises shrinking the uncorrugated portions and simultaneously increasing the thickness thereof while maintaining the portions to be corrugated at substantially the original thickness, corrugating said latter portions and then forming a seam along the uncorrugated portions.

8. In a method of the class described, the following steps; shrinking the marginal portion of a sheet of metal to produce a fullness or surplus of metal at other portions, and corrugating said other portions to take up fullness or surplus thereof.

9. The method of forming a tube of the class described, which comprises the following steps: forming a plain sheet into a gutter having a flat bottom wall and flat side walls at substantially right angles to the bottom wall and flat marginal flanges lying substantially parallel to the bottom wall, fore-shortening the entire gutter and simultaneously forming corrugations in the bottom wall of the gutter, said corrugations extending into and through the side walls of the gutter.

10. In the method of forming a tube of the class described, the combination of the following steps: forming a plain sheet into a gutter having a bottom wall and side walls, said walls being substantially at right angles to the bottom wall, fore-shortening the gutter to thicken the side walls of the gutter and corrugating the bottom wall of the gutter while maintaining the metal of said corrugations at substantially the original thickness.

11. The method of forming a tube of the class described, the combination of the following steps: bending a plain sheet into the form of a gutter having bottom walls and side walls, the side walls lying at substantially right angles to the general plane of the bottom wall of the gutter and pressing the bottom wall inwardly in a semicircular depression, said pressure being extended through the side walls to crush them edge-wise to form a complete transverse semicircular corrugation.

12. The method of forming a sheet of metal into a tube which includes the following steps, forming the sheet into side walls,

end walls and a joining margin, and forming corrugations in the side walls extending through the end walls.

13. In the method of forming a sheet into a tube, the combination of the following steps: forming the sheet metal into a gutter having a bottom wall and side walls at substantially right angles to the bottom wall, then forcing a portion of the side wall inwardly to form a continuous groove transverse to the gutter and simultaneously crushing the side walls edgewise to form a fold of the metal at each end of the groove.

14. In the method of forming a sheet of metal into a tube, the combination of the following steps: forming the sheet into a gutter having a bottom wall and side walls at substantially right angles to the bottom wall, then pressing edgewise with a rounded forming tool upon the side walls and simultaneously pressing the bottom wall inwardly to form a complete transverse groove across the gutter.

15. The method of forming a tube from sheet metal which comprises forming the sheet into a pair of gutters with margins at their outer edges and margins between them, then forming a crease longitudinally centrally of said central margins, then folding the two gutters along said crease into the form of a tube, then joining the edges of said gutter to form a closed seam.

16. The method of forming a tube which comprises folding a sheet of metal continuously and progressively into a pair of gutters joined by an integral margin, then corrugating said gutters and simultaneously shrinking the metal along the central margin, then creasing the central margin and bending the two gutters toward each other and sealing the free edges of the same.

17. A radiator tube formed of sheet metal comprising unitary front and rear faces of greater thickness than the original sheet and corrugated side walls of a thickness substantially equal to or very slightly less than that of the original sheet.

18. In a radiator, a tube having front and rear faces and side walls, said side walls being corrugated in substantially semicircular corrugations, said front and rear faces having folds of metal about the ends of the corrugations.

19. In a radiator, a tube having front and rear faces and side walls, said side walls being corrugated in substantially semi-circular corrugations, said front and rear faces having folds of metal about the ends of the corrugations, said front and rear faces lying at substantially right angles to the side walls.

20. In a radiator, a tube having front and rear faces and side walls, said side walls being corrugated in substantially semi-circular corrugations, said front and rear

faces being thickened by shrinkage of the metal and having folds of metal about the ends of the corrugations.

21. In the process described, the steps of forming a sheet into a pair of gutters with a folding margin between the two gutters shrinking part of the gutters, including the folding margin to thicken the metal thereat smoothing out the metal along a folding line on said margin and folding said gutters toward each other on said line.

22. The method of forming out of sheet metal a corrugated tube having side walls and end walls which comprises laterally displacing parts of the metal which form the side walls, and simultaneously crushing together the adjacent parts of the metal forming the end walls.

In witness whereof, I hereunto subscribe my name this 8th day of October, A. D. 1918.

FRED M. OPITZ.
